UNITED STATES PATENT OFFICE

ROBERT B. SCHINDLER, OF SPRING CITY, PENNSYLVANIA

DESIGN FOR A STOCKING

Application filed February 2, 1932. Serial No. 42,715. Term of patent 3½ years.

To all whom it may concern:

Be it known that I, ROBERT B. SCHINDLER, a citizen of the United States, residing at Spring City, county of Chester and State of Pennsylvania, have invented a new, original, and ornamental Design for Stockings, of which the following is a specification, reference being had to the accompanying drawing, forming part thereof.

I claim:

The ornamental design for a stocking as shown.

ROBERT B. SCHINDLER.
